BOTTLE BREAKER

Homer H. Smith, Detroit, Mich.

Application October 24, 1950, Serial No. 191,883

12 Claims. (Cl. 241—99)

1

This invention relates to a liquor bottle breaker and more particularly to a device for destroying the empty liquor bottle as is required by many laws or ordinances.

Heretofore the bar tender or other person in a commercial establishment breaks the bottle with a hammer while holding it over a box but there was a disadvantage of injury in flying glass and furthermore this method was not fully effective in properly destroying the bottle.

It is the object of the present invention to provide a simple bottle breaking device within which the bottle is completely enclosed during breaking thereof and from which the broken parts of the bottle will descend by gravity into a storage container.

It is a further object of this invention to provide a simple bottle breaker construction which is sturdy, inexpensive to manufacture and fully effective for the intended purpose.

These and other objects will be seen from the following specification and claims in conjunction with the appended drawing in which—

Fig. 1 is a perspective view of the present bottle breaker.

Fig. 2 is a longitudinal section thereof.

Fig. 3 is a section taken on line 3—3 of Fig. 2.

Fig. 4 is a longitudinal section illustrating the variation in the construction of the bottle breaker; and

Fig. 5 is a section taken on line 5—5 of Fig. 4.

It will be understood that the above drawing illustrates merely a preferred embodiment of the invention and that other embodiments are contemplated within the scope of the claims hereinafter set out.

Referring to the drawing the bottle breaker includes an upright standard 11 of rectangular cross section preferably, upon which is mounted and secured the bottle breaker housing which is generally of U-shape in cross section as illustrated in Fig. 3.

Said housing includes spaced upright elongated side walls 12 which are joined and secured in overlapping relation to the opposite side walls of standard 11 as by the spaced screws 13. The upper open end of said housing includes the cover 14 which is hinged thereto as at 15 to provide access to the interior thereof for insertion of the empty bottle to be destroyed.

Said housing has an elongated interior space 16 bounded by said side walls 12 and by the front wall 17 as illustrated in Figs. 2 and 3.

Elongated bracket plate 18 is arranged in parallel spaced relation to said front wall and has a

2

pair of inwardly extending outturned leg elements 19 which are secured to the front wall 17 of said housing as by the screws or bolts 20 shown in Fig. 2.

5 Transverse bottle supporting pin 21 with enlarged head 22 upon its outer end slidably extends through corresponding openings in bracket 18 and said front wall and projects inwardly substantially across the opening 16 within said housing centrally thereof as illustrated in Figs. 2 and 3. It is thus apparent that the bottle 25 when inserted within said housing will be centrally supported upon pin 21 as illustrated in Fig. 2.

10 Washer 23 is suitably secured to pin 21 upon the outside of the housing front wall 17 and a coiled spring 24 is positioned around said pin and interposed between bracket 18 and said front wall whereby, if desired, the pin may be manually projected outwardly on manual application to the handle 22, and against the action of said spring to thus permit any portion of the broken bottle to drop downwardly through the lower open end of said housing.

15 Bottle 25 and its neck 26 is positioned within housing 12—17 and the cover 14 is closed as shown in Fig. 2 so as to be broken in a manner and by the structure now described. Retractable shaft 27 is arranged at right angles to the longitudinal axis of said housing and is slidably positioned through corresponding openings in the bracket 18 and said front wall 17 whereby the inner end of said shaft is positioned closely adjacent the central portion of the empty bottle 25 as shown in Fig. 2.

20 Said shaft has a head 28 upon its outer end and a coiled spring 29 is positioned upon said shaft between said head and said bracket whereby upon an inward forceful blow to the shaft head 28, such as by a hammer, the inner end of shaft 27 will be projected inwardly for breaking engagement with the bottle and by said spring will be returned automatically to the position shown in Fig. 2.

25 A second bottle neck breaking shaft 30 with head 31 is similarly slidably positioned through corresponding openings in said bracket and said front wall for operative breaking engagement with the neck 26 of said bottle, said shaft 30 as well as the shaft 27 and the pin 21 being positioned in substantial vertical alignment on a center line of said bracket and housing. Furthermore coiled spring 32 is positioned upon shaft 30 between its head 31 and bracket 18 for automatically returning the same to its initial posi-

tion after having received a compressive inward blow such as by a hammer.

A preferably U-shaped clip 33 is positioned within said housing and is centrally joined and secured to the interior surface of front wall 17 of said housing by the bolt and nut 34.

The clip 33 is so arranged as shown in Figs. 2 and 3 so as to embrace the side walls of the bottle 25 to immovably retain the same in an upright position while it is being broken. It is contemplated however that the clip might be employed to merely engage the neck 26 of the bottle if desired.

In operation the upper head 31 would first be struck by a hammer to break off the neck 26 from the bottle and immediately thereafter the head 28 would be struck a blow to break the balance of the bottle body after which the broken pieces of glass would drop to the lower open end of said housing down into the box 33', which as in Fig. 1 shows a plurality of broken pieces of glass 34' therein.

In the event some of the pieces of broken glass do not fall past the pin 21, then said pin may be manually retracted by pulling on its head 22 after which said pin will return to its initial position as shown in Fig. 2 under the action of coiled spring 24.

A variation of the present invention is shown in Figs. 4 and 5 which includes upright rectangularly shaped in cross section standard 35 and the transversely U-shaped flexible housing 36 preferably constructed of rubber and which includes spaced substantially upright side walls 37. The housing 36—37 may be cut from a vehicle tire casing so as to provide the arcuate front wall portion 36 in conjunction with the inwardly extending side walls 37 which overlap portions of standard 35 and which side walls are pivotally joined to said standard at their lower ends as by the screws or bolts 38 arranged on opposite sides of said standard.

Housing 36 with lower open end 39 has an arcuate inturned upwardly extending top portion 40 which is slotted at 41 to permit portions of the side walls 37 to extend over the sides of standard 35. Housing 36 pivotally mounted at 38 at its lower end is normally and resiliently retained in the upright bottle enclosing position shown in Fig. 4 by means of the coiled springs 42 arranged on opposite sides of said housing with their upper ends joined at 43 to said standard and with their respective lower ends joined to opposite sides of said housing at points 44 by a suitable rivet or bolt.

Centrally arranged bottle supporting pin 45 is positioned within the lower end of housing 36 with the inner end of said pin projected into the central portion of the front face of standard 35 as shown in Figs. 4 and 5. The bottle 46 shown in dash lines and with the neck portion 47 is positioned within housing 36 which is first manually pivoted outwardly against the tension of springs 42 and thereafter released to assume the bottle breaking position shown in Fig. 4. The lower bottle breaking bolt 48 with head 49 at one end is laterally projected through a suitable transverse opening in housing 36 with the inner enlarged end 50 of said bolt arranged adjacent the wall of the bottle body. There is also provided a second shaft 51 with head 52 upon its outer end which is similarly projected transversely through the front wall of housing 36 with its inner enlarged end 53 adjacent the neck 47 of said bottle.

In operation it is apparent that a hammer

blow upon the head 52 of said bottle would break the same from the body of said bottle and a second hammer blow to the shaft head 49 will break up the body of said bottle and the pieces will fall downwardly by gravity through the opening 39 and down into a suitable storage container such as container 33' shown in Fig. 1.

Reinforcing links 54 are arranged upon the interior of said housing as illustrated in Fig. 4 and 10 respectively interconnect pivotal connections 38 on the standard and the spring connections 44 on the housing. Similar upright stiffeners 55 are employed upon opposite interior sides of said housing adjacent the outer ends of side walls 37 15 with the lower ends of said links joined at points 38 and with their upper ends joined to interior side wall portions as at points 56. It is contemplated however that the links 54 and 55 could be omitted if desired.

20 There is also provided a formed substantially U-shaped bottle neck engaging clip 57 which is centrally secured as at 58 to the front wall of standard 35 so as to retain the bottle in the upright position shown during the breaking operation.

25 By virtue of the inherent resiliency of housing 36 it is apparent that said housing will cause an automatic return movement of the bottle breaking shafts 48 and 51 after their receipt of a hammer blow. Thus in this construction no springs are required. Furthermore by employing the arcuate top surface portion 40 and by pivotally mounting the lower end of said housing to the standard a separately hinged cover is omitted.

30 Having described my invention, reference should now be had to the claims which follow for determining the scope thereof.

I claim:

1. A bottle breaker comprising an upright 40 standard, a hollow open ended elongated housing mounted in upright position upon said standard and having a front wall, a transverse bottle supporting pin projecting through a central portion of said front wall adjacent its lower end, and a 45 retractable shaft in parallel spaced relation to said pin and slidably projecting through said front wall for operative breaking engagement with a bottle supported within said housing upon application of an exterior longitudinal blow to said shaft.

2. A bottle breaker comprising an upright standard, a hollow open ended elongated housing mounted in upright position upon said standard and having a front wall, a transverse bottle supporting pin projecting through a central portion of said front wall adjacent its lower end, a retractable shaft in parallel spaced relation to said pin and slidably projecting through said front wall for operative breaking engagement with a

60 bottle supported within said housing upon application of an exterior longitudinal blow to said shaft, a hinged cover at the upper end of said housing, a head on said shaft, and a compressible shaft retracting spring mounted on said shaft 65 interposed between said head and said front wall.

3. A bottle breaker comprising an upright standard, a hollow open ended elongated housing mounted in upright position upon said standard and having a front wall, a transverse bottle supporting pin projecting through a central portion of said front wall adjacent its lower end, a pair of longitudinally spaced retractable shafts in parallel spaced relation to said pin and slidably projecting through said front wall for operative 70 breaking engagement with portions of a bottle

supported within said housing upon application of an exterior blow to said shafts, a hinged cover at the upper end of said housing, heads upon the outer ends of said shafts and compressible shaft retracting springs mounted on said shafts interposed between said head and said front wall.

4. A bottle breaker comprising an upright standard, a hollow open ended elongated housing mounted in upright position upon said standard and having a front wall, an elongated bracket spaced from said front wall and having formed end portions joined thereto, a transverse bottle supporting pin slidably extending through said bracket and a central portion of said front wall adjacent its lower end, and a retractable shaft in parallel spaced relation to said pin slidably projecting through said bracket and front wall for operative breaking engagement with the bottle supported within said housing upon application of an exterior blow to said shaft.

5. A bottle breaker comprising an upright standard, a hollow open ended elongated housing mounted in upright position upon said standard and having a front wall, an elongated bracket spaced from said front wall and having formed end portions joined thereto, a transverse bottle supporting pin slidably extending through said bracket and a central portion of said front wall adjacent its lower end, a retractable shaft in parallel spaced relation to said pin slidably projecting through said bracket and front wall for operative breaking engagement with the bottle supported within said housing upon application of an exterior blow to said shaft, a head on said shaft, and a compressible shaft retracting spring on said shaft interposed between said head and said bracket.

6. A bottle breaker comprising an upright standard, a hollow open ended elongated housing mounted in upright position upon said standard and having a front wall, an elongated bracket spaced from said front wall and having formed end portions joined thereto, a transverse bottle supporting pin slidably extending through said bracket and a central portion of said front wall adjacent its lower end, and a pair of longitudinally spaced retractable shafts in parallel spaced relation to said pin slidably projecting through said bracket and front wall for operative breaking engagement with the bottle supported within said housing upon application of an exterior blow to said shafts, a head on said shafts, and a compressible shaft retracting spring on each shaft interposed between its head and said bracket.

7. A bottle breaker comprising an upright standard, a hollow open ended elongated housing mounted in upright position upon said standard and having a front wall, an elongated bracket spaced from said front wall and having formed end portions joined thereto, a transverse bottle supporting pin slidably extending through said bracket and a central portion of said front wall adjacent its lower end, a retractable shaft in parallel spaced relation to said pin slidably projecting through said bracket and front wall for operative breaking engagement with the bottle supported within said housing upon application of an exterior blow to said shaft, a head on said shaft, a compressible shaft retracting spring on said shaft interposed between said head and said bracket, a cover on the upper end of said housing and a bottle engaging clip within said housing and secured centrally to the inner surface of said front wall.

8. A bottle breaker comprising an upright

standard, a hollow open ended elongated housing mounted in upright position upon said standard and having a front wall, an elongated bracket spaced from said front wall and having formed end portions joined thereto, a transverse bottle supporting pin slidably extending through said bracket and a central portion of said front wall adjacent its lower end, a retractable shaft in parallel spaced relation to said pin slidably projecting through said bracket and front wall for operative breaking engagement with the bottle supported within said housing upon application of an exterior blow to said shaft, a stop secured upon said pin adjacent said front wall, and a coiled spring on said pin between said stop and said bracket.

9. A bottle breaker comprising an upright standard, a hollow flexible housing longitudinally arcuate and of U shape in cross section and open at its lower end pivoted in upright position upon said standard, and with the opposed upright inner edges of the side walls of said housing extending over opposite sides of said standard, and coiled springs upon opposite sides of said housing secured at their one ends to said standard and at their opposite ends to said housing for maintaining the same in an upright position, a transverse bottle supporting pin on said standard, and a headed shaft parallel to said pin projecting through said housing for operative breaking engagement with a bottle in said housing.

10. A bottle breaker comprising an upright standard, a hollow flexible housing longitudinally arcuated and of U shape in cross section and open at its lower end pivoted at its lower end upon said standard, and with the opposed upright inner edges of the side walls of said housing extending over opposite sides of said standard, coiled springs upon opposite sides of said housing secured at their one ends to said standard and at their opposite ends to said housing for maintaining the same in an upright position, a transverse bottle supporting pin on said standard, and a headed shaft parallel to said pin projecting through said housing for operative breaking engagement with a bottle in said housing, and a bottle engaging clip within said housing centrally secured to said standard.

11. A bottle breaker comprising an upright standard, a hollow flexible housing longitudinally arcuate and of U shape in cross section and open at its lower end pivoted at its lower end upon said standard, and with the opposed upright inner edges of the side walls of said housing extending over opposite sides of said standard coiled springs upon opposite sides of said housing secured at their one ends to said standard and at their opposite ends to said housing for maintaining the same in an upright position, a transverse bottle supporting pin on said standard, and a pair of longitudinally spaced headed shafts parallel to said pin projecting inwardly through said housing with their inner ends adapted for operative breaking engagement with a bottle supported upon said pin within said housing, and with their heads engageable with the outer surface of said housing, and a bottle securing clip within said housing centrally secured to said standard.

12. A bottle breaker comprising a standard, a hollow flexible housing longitudinally arcuate and of U shape in cross section pivoted at one end upon said standard, and with the opposed edges of the side walls of said housing extending adjacent the opposite sides of said standard, a transverse bottle supporting pin on said stand-

ard, and a headed shaft projecting through said housing for operative breaking engagement with a bottle in said housing upon application of an exterior longitudinal blow to said shaft.
